GAS BURNER

Don M. Stainbrook, Detroit, Mich.

Application July 3, 1945, Serial No. 602,984

2 Claims. (Cl. 158—7)

My invention pertains to gas burners and more particularly to conversion heater units, suitable for installation into furnaces and boilers.

It is an object of my invention to provide gas burner units which may be conveniently installed and adjusted to provide the optimum conditions of combustion for gaseous fuel.

It is also an object of my invention to provide gas burner conversion units constructed of a few rugged and simple elements which may be conveniently manufactured, assembled, and installed, for burning gaseous fuel in various different furnaces or boilers.

Further objects and advantages are within the scope of my invention, such as relate to the arrangement, operation and function of the related elements of the structure, to various details of construction and to combinations of parts, elements per se, and to economies of manufacture and numerous other features as will be apparent from a consideration of the specification in conjunction with the drawing disclosing specific embodiments of the invention, in which:

Fig. 1 is a central sectional view taken vertically through a gas conversion unit, on line 1—1 of Fig. 2, the walls of an enclosing furnace being added; and

Fig. 2 is a plan view of one of the gas burner conversion units, shown alone without the furnace for clearness.

Referring more specifically to Figs. 1 and 2 of the drawing, I have illustratively disclosed one of my improved gas conversion heater units comprising a gas mixing and heating body 11 which is open at the top. The body 11 is preferably of a generally bowl or dish shaped conformation and it may be made of circular cross-section of various diameters selected to suit the fire-pots of the various different furnaces to be converted for burning fuel supplied in gaseous condition.

A cover 13 is provided of a size and shape suitable to be installed over the open top of the body 11 in a spaced relation so that a combustion gas delivery space 15 is provided between the peripheral edges of the cover and the body for projecting a gaseous flame adjacent a surface to be heated. The cover 13 may be supported upon adjustable support means 17 so that the width of the space 15 may be adjusted to the operating conditions or gas available at any particular installation. This may be readily accomplished by providing support screws 17 threaded through suitable apertures at spaced points around the periphery of the cover 13. The lower portions of screws 17 may be turned down to smaller di-

ameters to rotate smoothly in suitable apertures provided in the body 11, and pins 16 may be passed through the lower ends. By turning the screws 17, the cover 13 may be raised or lowered at various points around the periphery to vary and to equalize the combustion space 15 around the periphery, as desired, for any particular installation.

A gas inlet conduit 19 passes into the body 11 10 and opens under the cover plate 13 for discharging gas against the cover. Depending from the under side of the cover 13, and in close thermal connection therewith, is baffle means 21 surrounding and enclosing the upper end of the inlet conduit 19 for causing an abrupt reversal of the flow of the gas while at the same time conducting and radiating heat thereto from the cover. The baffle means 21 is of sufficiently larger cross-section than the inlet conduit 19 so that the admitted gas may easily reverse its course and flow downwardly where it turns and flows under the lower edges of the baffle means. This structure is readily provided by making the baffle 21 of tubular form and it may be cast integral with the cover plate or a piece of pipe of suitable length and diameter may be welded to the under side of the cover plate, as represented. A well or depression 23 is preferably provided in the central area of 15 the bottom of the body 11 and into which the lower end of the baffle 21 terminates in spaced relation so that the gas flow must again reverse and go upward before passing uniformly outward to the combustion space 15. To further heat the 20 gases and provide for uniform outward flow, a plurality of radially extending ribs 18 are provided projecting down into the body 11 from the underside of the cover 13, and these may be either integral or welded metal strips, as will be 25 understood.

The inlet conduit 19 passes down through the bottom of the well 23 where it connects with a pipe 25 which extends horizontally beyond the periphery of the body for connection with any 30 suitable source of natural or manufactured gas, and air in proper proportions, in a conventional manner. For this purpose, the terminus of the extended conduit 25 may diverge to a large bell mouth 27 to be covered by an air regulating 35 damper 29 which is centrally apertured for receiving a gas supply nozzle 31 in a manner common with the usual household gas burner. By turning the damper 29 the ratio of air drawn in by the injected jet of gas is regulated, as desired, and by means of any conventional valve 40

33 the rate of gas flow may be conveniently regulated, from the source (not shown).

For installation in a conventional hot air furnace 34 as represented in Fig. 1, my improved conversion gas burner is made of a suitable size so that the gas combustion space 15 is disposed adjacent and around the inside of the inner wall 35 of the furnace. The body 11 is supported by any substantial abutments 37 of fire bricks, or like refractory material, placed in the ash pit of the furnace to support the body at a suitable height. The horizontally extended pipe 25 is preferably extended out through the ash pit door-way 38, which may be closed by a suitable plate 39, as will be understood. After the burner is suitably installed and positioned, the air and gas flow are properly regulated by the damper 29 and valve 33 respectively. By adjusting the screws 17 the cover 13 is suitably spaced to project the gas flame 41 up along the inner surfaces of the firebox wall in the most effective manner. As the gas flows through the body, as represented generally by the arrows, it is heated and guided to flow uniformly to the peripheral combustion space 15.

It will be understood that the burner may be connected to receive gas from any suitable source of artificial or natural gas, and various well known automatic controls may be installed in well known arrangements (not shown), as desired, to suit various different installations.

It is apparent that within the scope of my invention modifications and different arrangements may be made other than herein disclosed, and the present disclosure is illustrative merely, the invention comprehending variations thereof.

I claim:

1. A gas burner comprising, a gas distributing body of circular cross-section open at the top, a flat disc shaped cover plate of a suitable size and shape to fit over the open top side of said body, peripherally disposed support screws for adjustably supporting said cover plate upon said body

spaced above the peripheral edges of the body to provide a combustion gas delivery space suitable for the operating conditions of an installation, a central well in said body, a gas inlet conduit opening into said body through the central well portion and opening adjacent the central area of said cover plate, a tubular baffle of larger cross-section than said inlet conduit, said tubular baffle projecting down from the cover plate in enclosing relation around the upper end of said gas inlet conduit and terminating at the lower end in said well to provide a gas flow space therefrom, said gas inlet conduit passing from the bottom of said body and extending horizontally beyond the periphery of said body and the terminus of said conduit being adapted for receiving gas fuel and air in proper mixing proportions from a suitable source.

2. Gas burning apparatus comprising, a bowl shaped body open at the top, a thermally conductive cover disposed on the open top of said body, adjustable means supporting said cover with its edges spaced from the body to provide a suitable peripheral fuel gas delivery space therearound, a gas inlet conduit passing into said body and opening adjacent the central area of the cover plate for projecting a suitable mixture of air and fuel gas into the body, baffle means of thermal conductive material depending from said cover in intimate heat exchange relation therewith and enclosing the adjacent end of said inlet conduit to provide a reverse flow path for gas and air discharge from the inlet conduit so that such gas and air is intermixed and heated as it is delivered toward the combustion space opening peripherally from said body, and thermally conductive gas flow guide means projecting down into said body from the underside of said cover and extending between the central and the outer portions thereof for heating and smoothly guiding the outwardly flowing gases.

DON M. STAINBROOK.
